UNITED STATES PATENT OFFICE.

FRANK S. EGLOFF, OF RIVERSIDE, ILLINOIS, ASSIGNOR OF ONE-HALF TO RICHARD TODD, OF RIVERSIDE, ILLINOIS.

OIL BURNER.

Application filed October 19, 1925. Serial No. 63,254.

This invention which relates to an oil burner is designed particularly for use with building plants of various kinds. In its construction are embodied numerous features of improvement having to do with simplicity in the construction and assembly of its several components, and with general accessibility or removability of its principal units for purposes of repair, replacement, cleaning, or what not.

In addition the burner includes a flame spreader in the form of a manifold in which is preheated air for supporting combustion; an air control by which a selected volume of air is admitted for the support of combustion; and means which leads along a heated wall the incoming air whereby its temperature is raised to a high degree before combining with the fuel. These and other objects of my invention are more fully set forth in the description and claims to follow, taken in conjunction with the accompanying drawing, wherein an illustrative embodiment thereof is shown in the manner following:

Figure 1 is a central vertical section through the burner; and

Fig. 2 is a bottom plan view thereof.

The present burner comprises four major units—a burner head A whereon is carried a manifold B, a frame C in which the burner head is mounted, and a ring D loosely supported on the frame. These several parts, when assembled as shown in Fig. 1, are adapted to be placed within a furnace to which pipe connections are also extended to supply or remove oil, as required.

The burner head is in the general form of a hollow cone having an inner cylindrical wall 3 uniting with a bottom 4 which, in turn, is united with the lower edge of an outer cone wall 5 having its upper edge 6 terminating, by preference, slightly below the upper edge of the inner wall 3. Between the cone edge 6 and the proximate wall is an opening 7, shown as annular, which communicates with the chamber 8 which is formed interiorly of the burner head by the walls and bottom just described. A fuel inlet 9 is connected with the burner head so as to deliver oil into this chamber.

The conical wall 5 of the burner head is shown as smooth and relatively steep, and near its base is provided with an outwardly extending shoulder 10, and extending be-

low and outwardly from the cone base is an annular primary trough 11 surrounded by a peripheral wall 12 which, after extending upwardly to a point about level with the shoulder 10, is outwardly flared as at 13.

A burner head of this general description is mounted within the frame C which, as shown, comprises inner and outer cylindrical walls 14 and 15, respectively, between which is an annular chamber with openings 16 in the bottom thereof. The burner which extends down into the space interiorly of the inner wall 14 is provided with a depending annulus 17 adapted to seat within a circular shoulder 18 in the upper portion of a wall 20 which is extended inwardly and upwardly from the inner frame wall 14. The shape of the wall 20 is such as to provide, together with the wall 14, an annular space constituting a secondary trough 20^a in which depends the primary trough 11. The diameters of the walls 12 and 14 are such that, when the parts are assembled in place, an annular space will intervene permitting oil to drain, if necessary, from the primary trough through holes 21 near the top of the wall 12 down into the secondary trough in the frame. Moreover, the frame support for the burner head is such as to preserve a clearance between the upper edge of the wall 14 and the outwardly flaring portion 13 of the adjacent wall 12. Any oil collecting in the secondary trough may drain therefrom through a pipe 22 which is provided for this purpose.

A connection by which the burner head is fixedly secured to its supporting frame may also be provided. As shown, this comprises a plurality of arms 23 which depend downwardly from the base of the burner head to connect with a common plate 24 wherein is an opening for a tube 25 having a head 26 adapted to engage the upper side of the plate. Complementary to the parts just described are other arms 27 extending inwardly from the frame wall 20 to connect with a common plate 28 wherein is an opening through which the tube is also extended. The end of the tube proximate thereto is threaded to receive a nut which bears against the under side of the plate so as to draw the burner head tightly to its seat in the frame. It will be noted that the open space interiorly of the frame and burner head is preserved substantially clear for up-

ward passage of air into the central portion of the burner head.

Upon the upper end of the circular wall 3 is rested a flame deflector which is in the form of an outwardly flaring manifold B having a removable cap or closure 30. Inferiorly of the manifold is a chamber from which air is discharged through openings 31 in the under side thereof against the inner side of the flame. The air is preheated within the manifold prior to its delivery therefrom to support combustion of the liquid fuel which flows down upon the conical walls of the burner head. I would have it noted that air so supplied proceeds downwardly in a current which is counter to that of the primary air supply which will now be described.

Associated with the frame C is the circular ring D which is adapted to be fitted upon a seat 32 provided in the upper edge of its outer wall 15. The ring includes an outer wall 33 which is upwardly extended from the outer frame wall 15; it is then bent over inwardly, as at 34, and then downwardly again to provide an inner wall 35 which flares inwardly, as shown. The lower inner edge of the ring is thus disposed below the top edge of the wall portion 13, and considerably to the inner side thereof, as shown. The effect of this is to cause air entering through the openings 16 to travel up along the wall 33 around its curved upper portions 34 and then downwardly again past the lower edge of the inner wall 35 which is constantly heated because of its proximity to the flame. This primary supply of air, heated in the manner just described, is required to pass around the lower edge of the wall 35, by which it is directed adjacent the base of the burner to the outside of the flame so as to support combustion of the fuel at that point. In this course of travel, the wall portion 13 assists in directing the air current around the wall 35 and in preventing any natural draft from interfering therewith.

The burner frame may be supported in any desirable manner. It may, for example, be provided with three or more legs 36 adapted to be screw-threaded within sockets 37 that are formed in bosses at desired points adjacent the frame base. I may also provide a means for controlling the volume of air passing through the openings 16 into the chamber between the frame walls. For this purpose, the frame may be provided adjacent its base with an outturned flange 38 to the under side of which is secured, as by bolts 39, lugs 40 which extend outwardly from a channel annulus 41 having in its under side a plurality of equidistantly spaced slots 42. These are adapted to register with other slots of similar size and spacing provided in a circular plate 43 which is sliding-

ly fitted within the channel annulus. By oscillating the plate 43 all the slots may be brought into or out of register, thereby varying the total area of the openings through which air is admitted into the chamber of the frame. Manipulation of the plate 43 may conveniently be effected with the aid of a rockable rod 44 having its end 45 bent to 90 degrees or so for engagement with the plate, as shown. The mounting in which the rod 44 may be rocked, is shown as a plate 46 which may, if desired, have a depending support from the channel annulus.

The present burner may use advantageously any suitable distillate whose gravity range is, say, from 32 to 38 degrees Baumé. The burner chamber is filled from the supply pipe so that the oil therein may burn at the opening 7, the oil burning at that point only producing the minimum amount of flame and heat. With increase in the flow of oil to the burner, a portion of the fuel which overflows upon the relatively steep conical walls 5 will spread and break up, the lighter part being consumed before reaching the base of the cone; the flow of the heavier portion of the fuel is retarded at the shoulder 10 of the cone, being consumed at that point or above so as to produce the maximum amount of flame and heat, the flame being spread in a desirable manner by means of the deflector B.

In case any valve controlling the flow of oil through the intake pipe is opened accidentally or otherwise, so as to allow oil to flow through the burner without being ignited, or in case of an excess of oil being fed to the burner, any such excess or overflow is collected first in the trough 11 from whence it may drain into the secondary trough 20 therebelow, if the flow be not checked. The outlet pipe 22 will remove all oil collecting in the secondary trough.

The combustion of the oil is supported in a very effective manner, by air being conducted to the flame from both its inner and outer sides. Inferiorly of the burner a quantity of air passes up to be preheated and distributed from the manifold in a manner which forms an air curtain between the deflector B and the flame below, thus tending to ensure a complete combustion of the oil with a consequent minimization of carbonization and vibration. The manifold is especially effective in raising the air temperature sufficiently to harmonize with the flash point of a low grade fuel.

The main supply of air to the burner which passes through the frame chamber is controllable as to volume, velocity, and point of contact with the oil. In this manner a proper mixture of air with oil is assured, such as is necessary for complete combustion of the fuel. By the use of cone walls which are relatively steep and smooth, I am able

to secure a maximum amount of fuel spread, with a minimum amount of thickness of the oil flow exposed to the current of air which passes through the openings 16. The result 5 of this is a clean combustion and maximum efficiency of the fuel used. The oil supply inside the burner cone is preheated to the boiling point by the heat from the burning oil on the exterior of the burner cone, therefore 10 by further increasing the general efficiency of the apparatus. A burner answering to the preceding description may be advantageously operated with a natural draft of air and gravity feed of fuel, thus conducing to 15 the general simplicity of the mechanism.

I claim:-

1. In an apparatus of the kind described, the combination of a frame having an outer annular chamber and an inner annular 20 trough, a burner head extending above the frame and provided with an annular trough, which depends into the trough first mentioned, means depending from the burner head adapted to rest upon the frame 25 whereby a mounting thereupon is provided for the burner head, means for directing air passing through the chamber toward the burner head base, and means for supplying liquid fuel to the burner head, substantially 30 as described.

2. In an apparatus of the kind described, a conical burner head having a hollow fuel chamber with an annular opening adjacent the top through which fuel may pass to 5 flow down upon the conical wall of the burner head where the heat resulting from combustion thereof is conducted in part to the fuel within the chamber, there being a vertical air passage within the fuel chamber 10 extending above the top thereof, a manifold above the burner opening having an upwardly and outwardly extending wall which serves as a flame deflector, there being a plurality of openings in said wall through 15 which preheated air within the manifold is delivered to the flame to support combustion thereof, substantially as described.

3. In an apparatus of the kind described, the combination of a burner head having an 20 annular trough the outer wall of which is outwardly flared adjacent its upper edge, a

frame in which the burner head is mounted having a lower secondary trough wherein the burner trough is receivable, there being means for permitting an excess of liquid 55 fuel to drain from the burner trough into the frame trough, means for conducting air through the frame and for delivering the same within the burner trough adjacent the base of the burner head, and other means for 60 conducting air through the burner head and delivering the same to the flame from above, substantially as described.

4. An apparatus of the kind described in which is comprised a burner head having adjacent its base an annular trough surrounded by a wall whose upper edge is outwardly flared, a frame in which the burner head is supported having hollow circular walls providing an annular chamber therewithin, the 70 upper edge of the inner wall terminating short of the flared edge of the trough wall and the outer frame wall being extended upwardly past said flared edge, then inwardly and downwardly below said edge to terminate within the trough, a passage being thereby provided for the travel of air upwardly through the frame chamber, wherein it is deflected outwardly by the flaring edge 75 of the trough, and then inwardly and downwardly by the curved upper portion of the outer frame wall whereby the air is discharged into the trough adjacent the base of the burner head, substantially as described. 80

5. An apparatus of the kind described in which is comprised a frame having inner and outer walls between which is an annular chamber, a ring supported on the outer frame wall and extending upwardly, then 90 inwardly and downwardly to provide an inside edge which terminates inside of the inner frame wall but at a point thereabove, and a burner head supported in the frame having adjacent its base an annular trough 95 surrounded by a wall whose upper edge is outwardly flared and disposed above the inner wall of the frame and to the outside of the inside edge of the ring thereupon, substantially as described.
